UNITED STATES PATENT OFFICE.

JULIUS J. BLAIR, OF ST. LOUIS, MISSOURI, ASSIGNOR TO BLEK COMPANY, MANUFACTURERS, OF ST. LOUIS, MISSOURI, A CORPORATION OF MISSOURI.

GARTER.

Application filed July 26, 1923. Serial No. 653,939.

To all whom it may concern:

Be it known that I, JULIUS J. BLAIR, a citizen of the United States, residing at the city of St. Louis, State of Missouri, have 5 invented a certain new and useful Improvement in Garters, of which the following is a specification, reference being had to the accompanying drawing forming a part thereof.

10 This invention relates to a certain new and useful improvement in garters and has for its chief object the provision of a garter which may be inexpensively manufactured, which is of simple form and exceedingly durable in construction, which is comfortable upon the leg, and which is efficient in the performance of its intended function.

With the above and other objects in view, my present invention resides in the novel 20 features of form, construction, arrangement, and combination of parts hereinafter described and afterwards pointed out in the claims.

In the accompanying drawing,

25 Figure 1 is an elevational view of a garter embodying my invention;

Figure 2 is a fragmental view of the garter; and

30 Figure 3 is an enlarged detail sectional view of the garter taken approximately on the line 3—3, Figure 2.

Referring now more in detail and by reference-characters to the drawing, which 35 illustrates a preferred embodiment of my invention, A indicates the leg-encircling band of the garter, which is preferably of suitable elastic webbing.

Disposed at one end of the band A, is a 40 relatively small plate 1 provided with a button or stud 2, for purposes shortly appearing, and slotted, as at 3, to accommodate a section of suitable fabric or the like 4, by means of which and a row of threadstitches 5 passed only through said section

45 4 and through the band A, as best seen in Figure 1, the plate 1 and its carried button 2 are independently fixed to the band

A. Suitably provided upon the other end 50 of band A, is a loop or hook 6 adapted for detachable engagement with the stud or button 2 to fasten the garter as a whole upon the leg of the wearer, as will be well understood.

B indicates a pad, which comprises match- 55 ing outer and inner members 7 and 8, re-

spectively, which are both preferably of suitable material, preferably leather, and which preferably also have the form or outline best seen in Figures 1 and 2. For purposes shortly appearing, upper or outer 60 pad member 7 is provided with an aperture 9.

C indicates the hose or sock engaging member of the garter, which comprises a suitably elongated tab 10 carrying a button 11 and a button-engaging loop or hook 12 of standard form and construction. The tab 10, however, is disposed at its one or upper end flatwise upon the upper face of inner or under pad-member 8 and fixed to 65 depend from the lower end thereof by an independent row of thread stitches 13.

With the member C so fixed upon said pad-member 8 and with the band A so disposed thereupon at its plate carrying-end 70 to bodily project laterally from the pad, as illustrated in Figures 1 and 2, the upper pad-member 7 is now disposed in matching registration upon the member 8 and rows of marginal thread-stitches 14 then passed 75 through the pad members 7 and 8, as well as through band A and tab 10, to secure the same together to complete the garter, the stud or button 2 being projected through said aperture 9 for convenient detachable 80 pivot engagement by the hook or loop 6.

And so constructed, it will be seen that the pad B fits flatwise and comfortably 85 without wrinkling upon the leg, entirely conceals the plate 1, and at the same time 90 prevents any engagement between the skin of the wearer and the metal loop 6. And further, should the pad-members 7 and 8 95 separate because of a breaking of the thread stitches 14 through perspiration or the like, the garter will continue to efficiently function, both the plate 1 and its stud 2 and the hose-engaging member C being independently fixed to the pad, as described.

I am aware that minor changes in the 100 form, construction, arrangement, and combination of the several parts of my new garter may be made and substituted for those herein shown and described without departing from the nature and principle 105 of my invention.

Having thus described my invention, what I claim and desire to secure by Letters Patent is:

1. A garter including, in combination, a 110

2
pad comprising a pair of superposed members fixed together, one of said members having an aperture, a leg-encircling band having an end fixed between the pad-members, a plate disposed upon said end of the band and concealed between the pad-members, a stud upon said plate protruding through said aperture, a loop carried by the other end of the band for detachable engagement upon the pad with the stud, and means comprising a fabric section upon the plate and thread-stitches passed only through said fabric section and the band for independently fastening the plate to the band.

2. A garter including, in combination, a pad comprising a pair of superposed companion members fixed together, one of said members having an aperture, a leg encircling band having an end disposed between the pad-members, a stud fixed upon said end of the band and protruding loosely through said aperture, a loop carried by said band at its other end for detachable engagement upon the pad with the protruding portion of the stud, a hose engaging member depending from, and having an end disposed between, the pad members, thread stitches passed only through the hose engaging member and one of the pad-members independently securing the hose-en-

gaging member to the pad, and additional securing thread stitches passed through both pad members, the band, and the hose-engaging members.

35

3. A garter including, in combination, a pad comprising a pair of superposed members, one of said members having an aperture, a leg-encircling band having an end disposed between the pad-members, a plate disposed upon said end of the band and concealed between the pad-members, a stud upon said plate protruding through said aperture, a loop carried by the other end of the band for detachable engagement upon the pad with the stud, a hose-engaging member depending from, and having an end disposed between, the pad-members, thread-stitches passed only through the hose-engaging-member and one of the pad-members for independently securing the hose-engaging member to the pad, additional securing thread-strokes passed through both pad-members, the band, and the hose-engaging member, and means comprising a fabric section upon the plate and thread-strokes passed only through said fabric section and the band for independently fastening the plate to the band.
